UNITED STATES PATENT OFFICE.

FRANCIS M. UNDERHILL, OF NEW YORK, N. Y., ASSIGNOR TO WHITALL,
TATUM & CO., OF SAME PLACE.

DESIGN FOR A JAR OR OINTMENT-POT.

SPECIFICATION forming part of Design No. 21,628, dated June 21, 1892.

Application filed May 6, 1892. Serial No. 432,084. Term of patent 14 years.

To all whom it may concern:

Be it known that I, FRANCIS M. UNDERHILL, a citizen of the United States, residing in the city, county, and State of New York, have invented and produced a new and original Design for an Ointment-Pot, of which the following is a specification, reference being had to the accompanying drawings, forming part thereof, wherein—

10 Figure 1 represents a side view, and Fig. 2 a vertical central section, of my ointment-pot.

The design relates to a new configuration of ointment-pot, its main features being the cylindrical body, with upper thread and bevel 15 and lower slope, as hereinafter described.

My ointment-pot (represented in the draw-

ings) has a cylindrical body *a*, with its upper portion screw-threaded, which screw-threaded portion is flush, or nearly so, with the exterior of the main body portion *a*. The body portion at the lower end slopes, as at *b*, in a very pronounced manner toward a narrower bottom *d*. The upper end of the body portion is beveled from the exterior to the perpendicular inner wall, as clearly shown at *e* in Fig. 2. 20 25

What I claim is—

The design for an ointment-pot, substantially as herein shown and described.

FRANCIS M. UNDERHILL.
